UNITED STATES PATENT OFFICE.

HARRY B. STEIN, OF CHICAGO, ILLINOIS.

WINDOW-HANGING DEVICE.

Application filed September 11, 1926. Serial No. 134,761.

My invention relates to window hanging device; and the main object of the invention is to provide and arrange such a device which will entirely conceal the sash cables and also the sash pulleys. Another object is to provide such a device with means which will act as sash parting means and will at the same time house and conceal the cables. A further object is to provide means on the device for concealing the cables and for also keeping out wind and weather from entering past the window into the room. Another object is to provide parting means and shielding means thereon for housing and concealing the cables, and further to provide spring means for co-operating with either said parting means or said shielding means to keep out wind and weather. A further object is to provide parting means and shielding means thereon which assists said parting means for housing and concealing the cables and which also acts as connecting means to connect the cable with its sash for retaining said sash in position vertically in the frame by means of the cable and its weights. And another object is to provide parting means for concealing the cables, and casing means at the top thereof for concealing the pulleys.

Other objects and advantages are accomplished with my invention, as will become apparent from the following description, taken in connection with the accompanying drawings, in which,

Fig. 1 is an elevational view of a window with upper and lower sash therein, having my invention applied thereto, parts being broken away;

Fig. 2 is a vertical sectional view, taken on line 2—2 of Fig. 1;

Fig. 3 is a horizontal sectional view, taken on line 3—3 of Fig. 1;

Fig. 4 is a slightly enlarged detailed view of the parts used where the sashes meet, and taken substantially on line 4—4 of Fig. 5;

Fig. 5 is a further enlarged view, similar to that in Fig. 3, but showing the elements with the lower sash in closed position and the upper sash in partly opened position;

Fig. 6 is an enlarged vertical sectional view of the pulley casing and connected parts;

Fig. 7 is a vertical sectional view on line 7—7 of Fig. 6, and

Fig. 8 is a horizontal sectional view on line 8—8 of Fig. 7.

In the drawings I have shown a preferred form of construction embodying my invention, and this comprises parting means which serves the purpose of the usual sash parting strip and is also made of sufficient width and size to house both of the sash cables. This means includes a parting member 10 which preferably has its edges bent transversely from the face part and then bent inwardly to form flanges 11, and this means also includes a member 12 which is fastened to the window frame, with suitable screws or elements, as best indicated in Fig. 5, and which has its middle portion fastened to the parting member 10, with screws 13 or 14 the like, and contains curved portions 14 which with flanges 11 of member 10 form separate guide channels for the sash cables 15.

Shielding means 16 is provided to keep out wind and weather, and is fastened to the lower sash 17 and to its cable 15, and a like means 16' is fastened to the upper sash 17' and to its cable 15', and also act to retain the window sashes in their vertical position in the frame by means of these cables and their weights 18 and 18'. Each means 16 is preferably arranged in the form of a flat casing having the inner edge part rounded and embracing and fastened upon the cable and traveling therewith in the guide channel 15 provided in the parting means; while the outer edge of means 16 is fastened to the sash, preferably in a notch provided therein. This means or casing 16 thus extends across the edge of the sash and substantially along the full length of the sash, thus serving as shielding means to co-operate with the parting means for keeping out wind and weather from entering around the window edge into the room. A cap 19 is mounted over the end 19 of each casing 16 to keep out dust and the like from entering the casing.

Spring means is provided which is preferably S-shaped in cross section, one member being mounted in a groove or channel arranged at each side in the inner member 12 of the parting means, and this spring means extends substantially the length of the lower sash and has an upper beveled end 20'; while a similar spring 21 is mounted above each member 20 in said groove in member 12 and

extends substantially the length of the upper sash, each having a lower beveled edge 21'. These members 20 and 21 are fastened in the parting means, with rivets or the like, and remain stationary with said means in the frame.

A yoke-shaped or channel member 23 is mounted in a groove provided in the edge of the sash, extends the length of each sash, and 10 tightly embraces or clamps the outer edge of each shielding member 16, being fastened to the sash, with screws or similar elements; and thus co-operates with member 16 to prevent wind and weather getting around the 15 outer edge of said shielding member. The sash and channel member may be readily slid outward from said shielding member, when the sash is to be taken out of the frame.

Means is provided for holding the casings 20 or shielding members positively fastened to the sash, and this means includes a lever 24 pivoted with a pin or screw 25 in a notch in the sash, and releasably embracing the end of a rod 26 extending through the casing or 25 member 16 and beyond the same. The lever thus engages outward of member 16 and its cap 19, to retain the same vertically in position on the sash, but by loosening screw 25 the lever is readily lifted off from rod 26, 30 thus permitting ready separation of the sash and casing 16. Such a lever and rod arrangement is placed at each side of each sash, especially at the top of the lower sash and the bottom of the upper sash, and this 35 rod may be extended throughout the length of casing 16 to reinforce its edge located in member 23; while at the bottom of the lower sash, and if desired also at the top of the upper sash, I may use curved or U-shaped 40 members 27, removably mounted with screws or the like in grooves in the ends of said sashes, and these members 27 extend slightly beyond each side edge of the sash outward along members 16 and their caps 19, thus 45 retaining the members 16 in position. These members 27 are preferably made of spring metal and are arranged to engage the top and bottom of the frame so as to make an airtight connection.

50 A pulley casing 28 is provided at the top of the parting means 10 and 12, and is constructed with two housing parts set at an angle to each other and wherein are pivotally mounted the pulleys 29, likewise arranged at an angle to converge over the parting means 55 and receive the cables 15 rising out of said parting means, and said casing parts and pulleys diverge at the opposite parts to accommodate the weights 18 and 18', as best indicated in Fig. 8. This casing 28 is preferably fastened to the upper end 12' of member 12, as with a screw or element 30, and is also attached with an angle iron 31 to a bracket 32 and thereby fastened, as with 5 screw 33 to the head 34' of the window

frame 34; and a bracket or angle iron 35 supports the diverging end of the casing, being fastened to frame 34, as with a screw 36.

In installing the device the casing with its 70 pulleys and cables is fastened to the top end 12' of the parting means and is therewith placed in the frame so that the casing rests on bracket 35, and bracket 32 is then fastened by screw 33 to the head 34' of the 75 frame, the curved springs 20 and 21 with the shielding members 16 being positioned with the cables in the parting means. The sashes with yoke-members 23 are then placed in position by sliding the yokes over the 80 outer edges of shielding means 16, and the levers 24 are thereafter placed over the end of rod 26 and fastened with screws 25 in their grooves on the sashes.

In operation and use of the device, when 85 the lower sash is in its closed position the upper spring members 21, on each side of the lower sash 17, will engage the edge 11' of flange 11, to keep out wind and weather; while the lower springs 20 are crowded outward, as indicated in inner lines in Fig. 5, and closely engage the shielding means 16, making a wind and weather tight fit therewith. As the sash is moved upward it engages along the edge 21' of upper spring 21 90 and crowds it outwardly away from the flange edge 11', and into the position shown in inner lines in Fig. 5, the spring then engaging the shielding means instead of the edge 11' of the parting means. Each of 95 these springs extend substantially the length of each sash, excepting for the cutaway beveled ends 20' and 21' at the meeting edges of the sashes.

What I claim as my invention and desire 105 to secure by Letters Patent is:

1. A window hanging device comprising sash parting means connected to the frame, and cable embracing means connected to and movable with the window sash to co-operate with and aid the parting means for containing and concealing the window cable, and keep out wind and weather.

2. A window hanging device comprising sash parting means arranged for concealing the window cable, and a shielding casing embracing and fastened to the cable and extending from the parting means across the edge of the sash and along the side thereof for substantially its entire length.

3. A window hanging device comprising sash parting means arranged for concealing the window cable, shielding means extending from the parting means along the window sash, and channel means attached 120 to the sash and embracing the outward edge of said shielding means but permitting ready separation of the sash and channel means from the shielding means and parting means.

4. A window hanging device comprising a cable and sash parting means arranged to house and conceal said cable, and means fastened to said cable and traveling therewith in said means and being fastened to the sash for holding it in position by means of said cable.
5. A window hanging device comprising a cable and sash parting means arranged for concealing the cable, shielding means extending from said cable to the sash and substantially the length thereof and traveling therewith, and means extending substantially the length of the sash, and along which said shielding means slides, to assist in keeping out wind and weather.
6. A window hanging device comprising a cable and sash parting means arranged for concealing the cable, shielding means extending from the cable and parting means to the sash, and curved spring means on said parting means arranged to engage and co-operate with either the parting means or the shielding means for keeping out wind and weather.
7. A window hanging device comprising a cable and sash parting means concealing the cable, shielding means extending from the parting means to the sash and moving with the sash, and curved spring means engaging the parting means, extending the length of the sash, and having a beveled end engageable by said shielding means to move the spring means away from the parting means, whereupon the shielding means and the spring means co-operate to keep out wind and weather.
8. A window hanging device comprising cables and sash parting means concealing the cables and having means to provide separate guide channels for said cables, shielding means connected to and extending from each sash to its cable and for the length of the sash, and curved spring means stationary with the channel means and arranged to be flexed by the shielding means and co-operate with the same to keep out wind and weather when the sash is in a certain position, and to engage the parting means, when the sash is in another position, to keep out wind and weather.
9. A window hanging device comprising sash parting means arranged to conceal the window cable, shielding means extending from the parting means and cable along the window sash, and fastening means on the ends of said shielding means and being readily attachable to and detachable from the ends of the window sash.
10. A window hanging device comprising sash parting means arranged to conceal the window cable, shielding means extending from the parting means and cable along the window sash, a rod projecting from said shielding means, and a lever on the end of the sash for engaging said rod and holding said shielding means attached to said sash, said lever being readily removable from said rod and said sash.
11. A window hanging device comprising parting means arranged for containing the cables of the window sashes, and a casing secured to the upper end of said parting means and having the cable pulleys set therein to diverge outward from said parting means, said device being arranged to entirely conceal the cables and also the pulleys.
12. A window hanging device comprising a parting member with means therein providing guide channels for separating the cables, means slidably at one side with the cables in said guide channels and being fastened with the other sides to the window sashes, and a pulley casing with diverging parts secured to the upper end of said parting member and channel means and having the pulleys arranged therein at an angle to place the converging parts over said guide channels and to place the diverging parts apart for accommodating the window weights.

In testimony whereof I have signed my name to this specification.

HARRY B. STEIN.
